(57) CLAIM

The ornamental design for a wrapper for chocolate, as shown and described.

DESCRIPTION

FIG. 1 is a top perspective view of a wrapper for chocolate with the chocolate in the wrapper;

FIG. 2 is a side perspective view thereof;

FIG. 3 is a side view shown with the chocolate removed;

FIG. 4 is a back view thereof; and,

FIG. 5 is a view of the wrapper for chocolate in an unassembled form.

The broken lines showing chocolates are for environmental purposes that form no part of the claim.
